SUCKER ROD SPACER

Filed March 22, 1927

INVENTOR.

P. R. G. Biedermann

BY Fred A. Taylor

ATTORNEY

UNITED STATES PATENT OFFICE.

PAUL R. G. BIEDERMANN, OF LOS ANGELES, CALIFORNIA.

SUCKER-ROD SPACER.

Application filed March 22, 1927. Serial No. 177,460.

My invention relates to spacers for sucker rods, and more particularly to those devices which have for their object to prevent the couplings on said sucker rods from wearing 5 through the tubing in pumping oil wells.

It is well known that in well drilling it is impossible to drill an absolutely straight hole. Hence, it is clear, that the sucker rod, which is attached to the well pump, and 10 which is suspended and moves freely within the tubing, accordingly cannot move in a true central position therein. As the couplings which connect the sucker rods to each other are of a larger diameter than the rods 15 themselves there is a tendency of said couplings to wear through the tubing, causing the fluid to run back into the well instead of being pumped to the surface. Obviously, this condition soon causes a serious loss to 20 the well-operator, especially since it is practically impossible to become aware of the same. Further, the frequent pulling of the tubing is quite expensive, and further results in the shutting down of the well for 25 at least from one to three days, causing additional losses in production. By the use of my invention all these deleterious features are effectively done away with.

It accordingly is an object of my invention to provide a novel form of device 30 which will properly maintain at all times the sucker rod in a central position within the tubing in its movement therein, and which consists of two elongated complementary members, preferably constructed of 35 suitable material, such as wood, hinged together by a novel form of clamping member positioned mid-way between the ends of said members, the free ends of which 40 clamping member are hinged together, the assembly being positioned on the sucker rod, thus effectively maintaining said rod in 45 proper central position in the tubing.

The above and further objects and advantages, which will hereinafter more fully appear, I attain by the device constructed in accordance with this specification and drawings forming a part of this application.

Reference is had to the accompanying 50 drawings, in which similar reference characters denote similar parts. In the drawings,

Fig. 1 is a side elevational view of the de-

vice positioned on the sucker rod in the well tubing,

Fig. 2 is a similar view of the side of the device opposite to that shown in Fig. 1, but removed from the tubing,

Fig. 3 is a fragmentary elevational detail view showing the manner in which the clamp 60 is set in the spacing members,

Fig. 4 is a similar view of the other part of the hinged clamp, and

Fig. 5 is a transverse cross-sectional view taken on the line 5—5, Fig. 1.

Describing my invention more in detail, the device is composed of two or more complementary spacing members or pieces 2 and 4, preferably constructed of wood, and of elongated form, each tapered as at 6, so 70 as to prevent the ends being caught by projections in the tubing as the assembly is swung back and forth therein.

The members 2 and 4 are formed from a cylindrical piece having a longitudinal bore 75 therethrough, said members or pieces being of a cross-sectional area subtended by arcs of no more than 120 degrees, or one-third of a circle, the inner arc of each forming the surface for engaging with the sucker 80 rod, designated by the numeral 8. This, when said pieces or members are positioned on the sucker rod, leaves two wedge-shaped passages 10, subtending arcs of 60 degrees, or one-sixth of a circumference, forming, in 85 addition to the clearance between the device and the tubing, passages for the fluid. See more particularly Fig. 5.

Each of the pieces 2 and 4 is cut away as at 12, for the reception of the clamp, designated generally by the numeral 14. This cut-out or cut-away portion is preferably positioned midway between the ends of the pieces 2 and 4 for convenience in assembly and manipulation.

As seen more particularly in Fig. 5, the clamp 14 is formed of two parts 16 and 18, curved as shown to conform to the curvature of the sucker rod 8, hinged together as at 20, the free ends 22 and 24 being cut away in complementary form so that they will interengage, the parts, if desired, being bent outwardly or inwardly to provide a passage for the reception of a locking key 26, which, when the device is in position on the sucker 100 rod 8, may be bent and hammered down at 105

both ends so that there will be no projections to catch into anything, and at the same time form an effective lock which, when desired, may be speedily opened by a cold 5 chisel or the like. See Figs. 1 and 5.

Any preferred way of securing the two parts of the clamp 14 to the pieces 2 and 4 may be used. Fig. 1 illustrates a convenient way of doing this, a rivet 17, counter-sunk in the wood of the pieces, forming an effective means of holding the curved part 16 of the clamp in the cut-away portion of 10 said pieces.

To remove the device from the sucker rod 15 8, the bent-over portions 25 of the locking pin or key 26 are straightened by any convenient implement, and said key removed after which it is a simple matter to swing 20 the hinged parts away from the sucker rod. To assemble, the hinged portions permit the assembly to be positioned on the sucker rod 25 8, the key 26 pushed home through the bent-over parts 22, after which the upper and lower parts of the key 26 are hammered into position as hereinbefore explained. New 30 keys are used when needed.

Of course any preferred number of devices, such as described, are used on the sucker rods, preferably one for each joint, 35 said devices being either finally locked to the rods, or may be so locked thereto that they can be slideable thereon, the hinged clamp forming an effective and exceedingly simple means for quickly placing the device 40 on the rods or removing the same therefrom, when the wooden pieces become worn and need replacement.

Moreover I have shown but two devices 2 and 4, it will be clear that any preferred 45 number of such devices may be used.

Attention is also directed to the fact that there is a positive lock, the clamp itself being locked, and at the same time permits the device to be locked on the sucker rods. This 50 insures that the device cannot be dislocated, even when the wooden parts are badly worn. Moreover, the number of wooden pieces, is immaterial—any convenient number may be used. When the device is locked on the 55 rods, it becomes one single entity, and this depends neither on the rods nor the tubing to make it so. By the use of the hinged clamp the spacers may be quickly applied, without any adjustment. All that is required is to push the key home, and hammer one or both ends into position.

The device cannot come apart even though the wooden parts become badly worn, and will reduce to a minimum the wear on the 60 tubing, keeping the rods at all times in a central position therein.

While I have thus described my invention with great particularity, it will be clear

that the same may be modified throughout a wide range. I accordingly do not propose 65 to be limited to the exact details of construction shown and described, but reserve the right in practice to make any and all modifications thereof that fall within the scope of the appended claims. 70

I claim as my invention:

1. A sucker rod spacer including a set of spaced apart, symmetrically positioned, complementary spacing members adapted to protect said sucker rod, each of said members being cut away to provide a set of aligned depressions, a curved and hinged clamping device countersunk in said depressions and secured to said members, and a detachable key for holding said device together, said hinge and said key being positioned within the spaces between said members. 75

2. A device of the class described including a rod, a protective means for said rod, 80 said means comprising a set of elongated spaced-apart complementary members, each of said members having a cylindrical cross-sectional area not in excess of one-third that of a right cylinder, and a clamping device, 85 distinct and separate from said members, and secured thereto, for holding said members to said rod, said clamping device being hinged and keyed together, said hinge and key being positioned in the spaces between 90 said members. 95

3. A sucker rod spacer including a pair of complementary members, spaced apart to provide passages for a circulating medium, a clamp countersunk internally in said members and secured thereto, for clamping said members to said rod, a hinge associated with said clamp, said hinge being positioned in one of the spaces between said members and protected thereby, and a vertical key for holding said clamp and said members in detachable relation with said rod, said key being also positioned in one of said spaces and protected thereby. 100 105

4. A device for centrally positioning the sucker rod within an oil well tubing, including a pair of spaced apart complementary cylindrical members, internally curved to fit said rod, a hinged clamp, countersunk in said members and secured thereto, said hinge being positioned within one of the spaces between said members and thus protected thereby, and a detachable key for detachably connecting the other ends of said clamp, and also positioned in one of said spaces, and thus protected thereby, one of the ends of said key being adapted to be bent over said clamp to prevent its accidental removal. 110 115 120

In testimony whereof I have signed my name to this specification.

PAUL R. G. BIEDERMANN.
